UNITED STATES PATENT OFFICE.

RAY STANTON, OF PORTLAND, OREGON.

JOINT-SUPPORT.

SPECIFICATION forming part of Letters Patent No. 724,349, dated March 31, 1903.

Application filed June 24, 1902. Serial No. 113,036. (No model.)

To all whom it may concern:

Be it known that I, RAY STANTON, residing at Portland, in the county of Multnomah and State of Oregon, have invented a new and 5 Improved Joint-Support, of which the following is a specification.

My invention is in the nature of an improved plumber's supply article, and it seeks to provide a simple and effective nipple or 10 hard-metal tubular member having one end especially designed for conveniently, accurately, and positively supporting a soft-metal pipe-section during the operation of making a wiped joint for firmly connecting the nipple or hard-metal member with the soft-metal 15 or lead pipe-section.

My invention comprehends a peculiar and novel construction of nipple or hard-metal tubular section, and in its more specific nature 20 it embodies an improved wiped joint, hereinafter fully described in detail and specifically pointed out in the appended claims, reference being had to the accompanying drawings, in which—

25 Figure 1 is a perspective view of my improved article of manufacture. Fig. 2 is a vertical section of the same, showing the lead pipe-section slipped over its joint-sustaining end. Fig. 3 shows the lead pipe-section bent 30 to engage the groove of the nipple-neck and hung on the end enlargement or bead thereof. Fig. 4 is a view of the wiped joint complete. Figs. 5 and 6 are horizontal sections taken on the lines 5 and 6 of Fig. 4.

35 The joint-holder 1 (shown in the drawings) may have its body or threaded end made of any desired form, as the formation of said end of the joint-holder forms no part of my invention, which is confined to the peculiar 40 shape of the nipple end thereof, (designated by 2 in the drawings.) The nipple end 2 has an annular groove 2^a, the lower edge of which merges with a bead or pendent portion 2^b, which has a greater diameter than the body 45 portion 2^a, as clearly indicated by the horizontal sections 5 and 6, the reason for which will be readily apparent by reference to Fig. 2, in which the lead pipe-section B is shown over the nipple end of the holder to a point 50 under the groove 2^a.

By forming the bead or lower end of the nipple 1 of a greater diameter than that part

of the nipple above the groove the upper end b of the pipe B will be spaced apart from the nipple portion 2, and thereby permit of readily 55 bending or swaging the said pipe end b inwardly and downwardly to produce an annular inturned rim b' for projecting into the groove 2^a of the nipple, and thereby provide positive means for suspending the pipe B 60 from the solid-metal holder 1 without requiring any special sustaining means and for maintaining it in a proper connection with the said holder 1 during the operation of putting on the external solder and making a clean 65 and effective wiped joint.

I am aware that a hard-metal coupling member has heretofore been provided having a special construction of nipple end whereby to provide for conveniently making a sweat-joint, (see Patent No. 689,684, dated December 24, 1901; but the nipple end in the construction disclosed in said patent is not adapted and could not be practically employed for making wiped joints. In the said patent the 75 nipple end of the coupling below its groove is of less diameter than the body of the nipple above the groove, whereby to form an offset, so that the upper end of the lead pipe to be fitted on the hard-metal member will crowd 80 the solder (caught in the groove in the said patented construction by dipping the nipple into a solder-bath) out sufficiently to produce a solder rim for insuring a firm sweat-joint. 85

My construction of nipple differentiates from what has heretofore been provided in this line, so far as I know, in the peculiar correlative formation of the nipple-shank 2, its groove 2^a, and the pendent or bead portion below the groove, and in my construction the groove 2^a is not intended to gather solder at all, and the nipple therefore requires no dipping. The increased diameter of the lower end provides, as it were, a bearing-point over which to swage or bend inward the upper end b' of the pipe B, and by reason of the decreased diameter of that part of the nipple above the groove sufficient space is provided to permit a proper bending inward 95 of the said end b of the pipe B, and, furthermore, by reason thereof a firm grip of the said end b' in the groove 2^a is assured for sustaining the pipe B properly upon the mem- 100

ber 1 without the necessity of steadyng the same by hand or otherwise, thereby leaving both hands of the plumber free for putting on the wiped-joint lead, a result not to be had in the type of sweat-joint construction before referred to, for in that type of joint the lead pipe must be steadied or otherwise while the sweat-joint is being made.

Having thus described my invention, what 10 I claim, and desire to secure by Letters Patent, is—

In a wiped joint, the combination of a hard-metal member having a pendent portion of reduced diameter at the nipple end, and an

annular groove at the point where the said 15 reduced portion merges with the wide part of the nipple end, a soft-metal pipe fitting over the reduced end of the nipple, and having in-turned edges for engaging the groove in the nipple, and a lead wiping surrounding the 20 nipple end of the hard-metal member and the upper end of the lead pipe, substantially as shown and for the purposes described.

RAY STANTON.
